CLAIM

The ornamental design for security light with sensor, as shown and described.

DESCRIPTION

FIG. 1 is a front perspective view of a security light with sensor showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view thereof, wherein the security light with sensor is rotated on a top end of a lamp; FIG. 9 is a front perspective view thereof, wherein a lamp is rotated to a downward illuminating angle; and,

FIG. 10 is a front view thereof, wherein the security light with sensor is rotated toward another angle on the top end of a lamp.

The broken lines in the disclosure represents the unclaimed boundary between claimed and unclaimed portions of the design or portions of the security light with sensor which form no part of the claimed design.
